UNITED STATES PATENT OFFICE.

RICHARD VALLIANT, OF VICTORY, WISCONSIN.

POST-DRILL ATTACHMENT.

No. 896,601.

Specification of Letters Patent.

Patented Aug. 18, 1908.

Application filed September 19, 1906. Serial No. 335,290.

To all whom it may concern:

Be it known that I, RICHARD VALLIANT, a citizen of the United States, residing at Victory, in the county of Vernon and State of Wisconsin, have invented new and useful Improvements in Post-Drill Attachments, of which the following is a specification.

This invention relates to post drill attachments, and one of the principal objects of the same is to provide an attachment for machines of this kind which can be readily adjusted to fit die blocks or taps of different sizes and hold them in position for use.

Another object of my invention is to provide a spring clamp attachment for post drills with means for attaching the clamp to chucks of differing sizes, said clamp being provided with resilient means for clamping die blocks or taps of differing sizes.

Still another object of my invention is to provide a spring clamp for attachment to a drill chuck and for holding die blocks and taps of different sizes, and to provide means for supporting said attachment upon the frame during the operation of changing the taps or die blocks in the clamp.

These and other objects may be attained by means of the construction illustrated in the accompanying drawing, in which:

Figure 1 is a side view of a post drill having my attachment connected thereto. Fig. 2 is a front elevation of the same. Fig. 3 is a plan view of my attachment. Fig. 4 is a sectional view through the die block holder or tap holder. Fig. 5 is a side elevation of the hook for supporting the attachment during the operation of changing the die blocks or tap.

Referring to the drawing for a more particular description of my invention, the numeral 1 designates the drill shaft of an ordinary post drill provided with a chuck 2 of the usual or any preferred construction, and 3 is a vise for holding the bolts or nuts, said vise being supported upon the seat 4 of the drill.

My attachment consists of a double spring clamp comprising the upper ring 5 and the lower ring 6 connected by diverging arms 7. The ring 5 is adapted to be secured to a drill chuck 2 which may be of large or small diameter, said ring 5 being resilient and provided with outwardly extending lugs 8 through which a binding screw 9 is passed. The screw 9 may be turned for drawing together the two lugs 8 for clamping the ring 5 upon

the chuck and a set screw 10 passing through the ring, is designed to firmly hold the ring 5 in engagement with said chuck. The arms 7 are formed integral with the ring 5 and at the lower ends of said arms the die block or tap holding ring 6 is formed thereon. The ring 6 is provided with outwardly projecting lugs 11 provided with registering threaded apertures for the binding screw 12. Set screws 13 pass through the ring 6 at diametrically opposite points for holding a die block or tap holder of any suitable dimensions.

The die block or tap holder shown in Fig. 4, comprises a recessed block 14 in which a pair of dogs 15 are fitted to slide toward and from each other to hold a die or tap of any required style, said dogs being held in adjusted position by means of the binding screws 16. The die block 14 is adapted to be fitted within the ring 6 and clamped therein by means of the binding screw 12 and the set screw 13.

A spring mounted supporting hook is shown in Fig. 5 which comprises a clamping ring 17 adapted to be secured, as shown, upon a boss or hub for the lower end of the spindle bearing upon the frame by means of a binding screw 18. A lug 19 depends from the ring 17 and a hook or latch device 20 is pivoted at 21 to the outwardly projecting lug 22 on said ring. A spring 23 is mounted upon outwardly projecting pins 24 formed upon the hook 20 and upon the lug 19, said spring being secured at its ends to said pins to hold the hook 20 normally in the position shown in Fig. 1. When it is desired to use the attachment the union nut 26 which forms the usual swivel connection between the feed screw 25 and the spindle, is released and the feed screw run upward. The spindle is then free to slide through the driving pinion which is splined to it as usual, and is in condition to be used for cutting screw threads. When it is desired to change work or the die block or tap, the spindle is slid upward, and the hook 20 caused to engage the lower edge of the ring 6.

The operation of my invention may be readily understood from the foregoing.

My attachment is formed of resilient material and the ring 5 is of a size to fit drill chucks of various diameters and can be quickly attached thereto by turning the screw 9 and the set screw 10, while the ring 6 will hold the die block or tap of different sizes. The adjustments can be quickly made

and the attachment, being of simple construction, cannot readily get out of order and will operate efficiently for its purpose.

Having thus described the invention, what 5 I claim is:

In a screw threading machine, a spindle free to slide vertically, a driving wheel splined thereon, a tool holder on the spindle, a latch on the frame, and means on the spin-

dle adapted to be engaged by the latch when 10 the spindle is in raised position, substantially as specified.

In testimony whereof, I affix my signature in presence of two witnesses.

RICHARD VALLIANT.
